Attorney

UNITED STATES PATENT OFFICE.

JOHN AUGUSTUS HOGE, OF TREMONT, LOUISIANA.

MICROMETER.

Application filed September 22, 1926. Serial No. 136,997.

This invention relates to an improved micrometer and has more particular reference to an inside micrometer head.

Briefly, the improved instrument comprises a cylindrical shell having means at one end to accommodate a manually adjustable micrometer and having means at its opposite end accommodating an automatically adjustable means for cooperation with the manually adjusted means, to permit more accurate measurement to be obtained.

More specifically, the invention relates to a cylindrical shell having an internally screw threaded cylinder at one end to accommodate the manually adjustable micrometer, the shell being constructed at its opposite end to accommodate a spring pressed plunger and measuring element which actuates an indicator such as may be more readily visualized under conditions such as make the reading of the ordinary micrometer difficult and uncertain.

Other features and advantages will become apparent during the course of the following description.

In the accompanying drawings, wherein like reference characters are employed to designate like parts throughout the same:

Figure 1 is a top plan view of a measuring instrument constructed in accordance with the invention,

Fig. 2 is a central longitudinal view through the same, showing parts in elevation,

Fig. 3 is a transverse section taken approximately upon the plane of the line 3—3 of Fig. 1 looking in the direction of the arrow.

Referring to the drawings in detail, it will be seen that the reference character 1 designates the cylindrical shell which is open at its opposite ends and provided at its center with a partition 2. Extending from one side of the partition is a cylinder 3 located within the shell and terminating in spaced relation from the left-hand end. In this connection it will be noted that the left-hand end is provided with a bevel equipped with customary graduations 4. Moreover, it will be noted that the cylinder 3 is internally screw-threaded and is spaced from the surrounding wall of the shell. This arrangement serves to accommodate a somewhat conventional form of manually adjustable inside micrometer. The part of the micrometer fitting into the screw threaded cylinder

3 cooperates with the aforesaid graduations 4 in an obvious manner. Extending from the opposite side of the partition is a relatively short cylindrical guide 5 in which the inner end portion of the plunger and the measuring stem 6 are slidably mounted. In this connection it will be noted that the partition 2 is provided with an opening for slideable passage of the inner free end portion 60 of the stem. Moreover, the stem is provided with a circular shoulder 65 slideable in the guide and a coiled spring 7 surrounds the stem between the shoulder and the partition and is confined in said guide. The 70 spring is exceptionally sensitive and will permit sliding movement of the stem as soon as a very slight pressure is brought to bear upon the same. The intermediate portion of the stem is provided with a gear 8 which cooperates with centrally disposed teeth 9 on a rotatably mounted shaft 10. The teeth are 75 formed by providing circumferentially spaced grooves in the shaft. Moreover, the shaft is pointed at one end, as at 10^a and 80 journaled in the shell and its opposite end is rotatably mounted in a part of the external gauge 11. In connection with the gauge it is to be stated that this includes a suitable dial and a transparent glass 12. In addition 85 there is a pointer 13 on the end of the shaft which cooperates with the dial which is preferably graduated in thousandths of an inch.

Movement of the stem in one direction is limited by the stop 14 and in the opposite direction it is limited by a similar stop 15. The end portion 16 extends through a closing head 17. This head is removably fitted into the adjacent end of the aforesaid cylindrical shell and the measuring stem normally projects a predetermined distance beyond the base of the head as shown. The head is provided on one side with a socket and located in this socket is a plate 18, a coil spring 19, and an operating member 20. 95 This member bears against the spring and is preferably provided on its outer end with a finger piece 21. The advantage of this construction is that in case the gauge cannot be read conveniently, the member 20 can be 100 tightened to hold the stem 6 in the position to which it has been moved. In turn, the indicating finger 13 will be held. In this way the instrument can be removed from the work and the gauge easily read, at 105 which the stem can be released to resume its normal position under the action of the

spring. The micrometer is of course used as any other inside micrometer but the particular construction shown will save much time and will insure accuracy in measurement. Instead of having to adjust by touch, as is now customary to one-thousandth of an inch, the stem can be adjusted within one hundred-thousandth of an inch while and in such position the dial can be conveniently read. The supplemental plunger and indicating means may be operated efficiently in conjunction with the manually adjustable micrometer (not shown) on the opposite end to insure an accurate and true measurement.

The advantages and construction will become apparent from the foregoing description and drawing. Therefore, a more lengthy description is thought unnecessary.

20 I claim;

1. In a measuring instrument, a shell provided with an internally screw-threaded cylinder at one end to accommodate a manually adjustable inside micrometer, a head at the 25 opposite open end of said shell, said head being provided with a guide opening, a stem mounted for sliding movement in said shell, and having one of its ends projectable through and beyond said guide opening and 30 its other end terminating in said shell, spring means connected with the last named end of the stem for normally pushing the opposite end of the same through said guide opening, a gear carried by the intermediate 35 portion of the stem, a shaft located in and extending across said cylinder at right angles to said stem and provided with teeth cooperable with said gear, a pointer carried

by one end of said shaft, and a gauge mounted on said body and including a dial 40 with which said pointer is cooperable.

2. In a measuring instrument, an open ended cylindrical shell provided with a central apertured partition, a cylinder located within one end portion of the shell and connected with said partition, said cylinder being provided with screw threads and being adapted to operate as a mounting and connecting means for a manually adjustable inside micrometer, a cylindrical guide carried by the opposite side of said partition, a head carried by one end of the shell and provided with a central guide opening in alignment with said cylindrical guide, a stem slidable through the opening in said partition at one end and through the opening in said head at its other end, said stem being provided with an intermediate gear, a shaft mounted for rotation in said shell and extending across said stem at right angles to the latter and provided with teeth cooperable with the teeth of said gear, spring means associated with the last named end of said stem and located in said cylindrical guide for pushing said stem outwardly 65 through and beyond the guide opening in said head, a pointer carried by said shaft, a gauge mounted on the body end including a dial with which said pointer is cooperable, and a manually adjusted retaining device 70 carried by said head and cooperable with said stem for holding the latter in a set position.

In testimony whereof I affix my signature.

JOHN AUGUSTUS HOGE.
